UNITED STATES PATENT OFFICE.

CHARLES BOOZ, OF BUFFALO, NEW YORK, ASSIGNOR TO HENRY M. BIRGE, OF SAME PLACE.

DESIGN FOR WALL-PAPER.

SPECIFICATION forming part of Design No. 26,133, dated September 29, 1896.

Application filed August 24, 1896. Serial No. 603,791. Term of patent 3½ years.

To all whom it may concern:

Be it known that I, CHARLES BOOZ, a citizen of the United States, residing at Buffalo, in the county of Erie and State of New York, 5 have invented and produced a new and original Design for Wall-Paper, of which the following is a specification, reference being had to the accompanying drawing, showing a part thereof.

10 The design consists of ornamental scrolls forming vase-like ornaments filled with flowers and leaves and festoons of flowers and leaves connecting said ornaments, as represented in the accompanying drawing.

15 The border for the design is also formed of ornamental scrolls forming vase-like ornaments filled with flowers and leaves and festoons of flowers and leaves connecting said ornaments with an ornamental scroll on each side of said vase-like ornaments, as shown in 20 the drawing.

What I claim is—

1. The design for wall-paper herein shown and described.
2. In the design for wall-paper the border 25 herein shown and described.

Witness my hand this 10th day of August, 1896.

CHARLES BOOZ.
